C. I. SWEET

ANIMATED TOY

Filed August 8, 1925

Inventor

C. I. Sweet

Attorney
Watson E. Coleman

UNITED STATES PATENT OFFICE.

CLIFFORD I. SWEET, OF HIGHLAND PARK, ILLINOIS.

ANIMATED TOY.

Application filed August 8, 1925. Serial No. 49,089.

To all whom it may concern:

Be it known that I, CLIFFORD I. SWEET, a citizen of the United States, residing at Highland Park, in the county of Lake and

- 5 State of Illinois, have invented certain new and useful Improvements in Animated Toys, of which the following is a specification, reference being had to the accompanying drawings.
- 10 This invention relates to toys, and particularly to that class of toys including a wheel supported body adapted to be pulled along and having figures thereon which are automatically caused to move as the toy proceeds on its way.

15 The general object of the invention is to provide a toy of this character which is very simple and entertaining to children and which has the form of a torpedo-shaped 20 motor car having a plurality of figures disposed apparently within the car, the car being provided with means whereby as it moves forward the figures are caused to alternately rise and fall.

25 A further object is to provide a device of this character which is so constructed that it may be very cheaply made at a minimum of expense and yet secure the effectiveness which is necessary.

30 My invention is illustrated in the accompanying drawing, wherein:—

Figure 1 is a top plan view of a toy constructed in accordance with my invention;

35 Figure 2 is a side elevation of the toy with the figures in place;

Figure 3 is a longitudinal sectional view thereof;

Figure 4 is an under side plan view;

Figure 5 is a vertical section on the line

40 5—5 of Figure 3;

Referring to this drawing, 10 designates a body having the similitude of a torpedo-shaped car, it being pointed at its rear end and blunt at its forward end and having a

45 cord or other means, indicated at 11, whereby the body may be drawn. Disposed in bearings at the front of the body is a transverse axle 12 and the front wheels 13. This axle 12 is cranked at its middle, as at 14.

50 The rear of the body is supported by a transverse axle 15 cranked at its middle and having supporting wheels 16. Both of these axles are supported by U-shaped brads 17 driven into the bottom of the body.

55 The body is formed with three or more vertical bores 18, and mounted for recipro-

cation in these bores are the three figures 19, 20 and 21. Each figure 19 and 20 has a body portion which fits the corresponding bore 18 very snugly but permits ready reciprocation therein. Each figure is cylindrical at its lower end and formed with a longitudinally extending slot 22. Pivoted within this slot upon a transverse pin 23 is a vertically extending connecting rod 24. The connecting rod for the figure 19 extends down to the crank 15, the connecting rod for the figure 21 extends down to the crank 14, and thus these two figures are reciprocated. The connecting rod 24 for the figure 20, however, extends downward to a lever 25 which is pivoted upon a transversely extending pivot pin 26. This lever at its forward end is longitudinally slotted, as at 27, and the cranked portion 15 engages within this slot, while the connecting rod 24 engages with the forward end of the lever 25. The body 10 between the rearmost bore and the bore for the figure 20 is longitudinally slotted, as at 28, and the upper portion of this lever fits within this slot and reciprocates therein. The pivot pin 26 is formed by a transversely extending piece of wire having re-bent ends which are driven into the bottom of the body. It will be obvious now that as this device is drawn over the ground the figures will reciprocate vertically and under some circumstances the figure 20 will descend as the figures 19 and 21 are ascending, or if the front wheels of the toy are lifted from the floor and then dropped back while the rear wheels continue to revolve, the alternation will be changed and figure 21 may under these circumstances ascend simultaneously with figure 20.

It will be noted that the figures 19, 20 and 21 may be formed by taking cylindrical rods of wood or like material and turning them in a shaper to provide the cylindrical body of the figure, or the head may be separate from the body and attached thereto in any manner, this being merely to make the bodies convenient for painting. The head is painted to represent a face and the figures are, of course, to be gaily colored, as is the body. The bores 18 may be readily bored on a jig or like machine and the bores extend clear through the body so that thus these bores may be very readily made and while the body is being formed upon the shaper, if desired. The kerf 28 supports the lever 25 against any lateral bending strain

which would tend to get this lever out of shape and cause it to bind, and by kerfing the lower ends of the figures, as at 22, they are held in proper position with relation 5 to the connecting rod 24 so that the figures will not tend to rotate but will keep their positions with their faces forward. This kerf likewise tends to prevent any bending of the corresponding connecting rod.

10 It will be seen that a toy of this kind is very simple, that it may be cheaply made, and that it is very attractive to children.

I claim:—

1. A toy of the character described including a solid body having cranked axles and wheels supporting the axles, the body being formed with vertical bores extending from the top of the body downward to the bottom of the body, a plurality of figures 20 having cylindrical lower portions simulating the bodies of the figures and fitting said bores and reciprocatable therein, and means operatively connecting said cranked axles to said figures and reciprocating the same in 25 said bores as the figure is drawn over the ground.

2. A toy of the character described comprising an elongated solid body having vertical bores extending through the body from 30 top to bottom thereof, transversely extending axles mounted upon the bottom of the body, each axle being cranked at its middle, two of said bores extending down to a point immediately above the crank of the corresponding axle, figures having elongated cylindrical base portions operating within said bores and simulating the bodies of said figures, connecting rods connecting two of 35 said figures to the cranks of the two axles respectively, a lever pivoted upon the bottom of the body, and a connecting rod connecting one of said figures to said lever and the other end of said lever being operatively 40 engaged by the crank of the other axle.

3. A toy of the character described comprising a solid body simulating a motor car and having three vertical bores extending therethrough, a pair of transversely extending axles mounted upon the body, each axle being cranked and the crank being disposed immediately below two of said bores, 45 elongated figures cylindrical in cross section and operating within said bores, the base of each figure being radially kerfed, a connecting rod having its ends disposed in said 50 kerf and pivoted to the figure and extending downward through said bores, the connecting rods of two of said figures being connected to the cranks of said axles, the bottom of the body between two of said bores 55 being formed with a longitudinally extending kerf, a lever partially disposed in said kerf and pivoted to the body, one end of the lever being slotted and receiving one of said cranks and the connecting rod of the 60 third figure being pivotally connected to said lever.

4. A toy of the character described comprising a solid body having two vertically disposed bores extending from top to bottom of the body and a kerf connecting said bores on the bottom of the body, a lever pivoted in said kerf and having its ends extending into said bores, a cranked axle mounted upon the bottom of the body and 70 extending across one of said bores and extending through the slot in the lever, vertically reciprocatable figures disposed within said bores and having transversely extending kerfs, and connecting rods pivoted 75 in said kerfs, one connecting rod being connected to the extremity of said lever, the other connecting rod being operatively connected to said crank.

In testimony whereof I hereunto affix my 80 signature.

CLIFFORD I. SWEET.
